HIRAM PERCY MAXIM, OF HARTFORD, CONNECTICUT, ASSIGNOR TO MAXIM SILENCER COMPANY, OF HARTFORD, CONNECTICUT, A CORPORATION OF CONNECTICUT.

SILENCER.

Application filed November 21, 1921. Serial No. 516,814.

The present invention relates to silencers such as are used for deadening the noise of the exhaust of gas engines, pneumatic machinery, or the like.

One type of gas engine muffler at present commonly used in automobiles comprises three sheet metal tubes coaxially arranged one within another and supported in spaced apart relation between cast header plates, the latter engaging the opposite ends of the tubes and being connected by tie bolts which rigidly bind the parts together so that three concentric annular chambers are formed. The gases are admitted to the central chamber through a port in one of the header plates and are caused, by suitably arranged perforations in the central and intermediate tubes, to travel in reversed directions through the three muffler chambers. The hot gases cause the sheet metal tubes and connecting bolts to expand to a different extent and as a result the tubes eventually become loosened or distorted so that they rattle disagreeably.

One of the objects of the present invention is to avoid the above mentioned difficulty and to this end the invention contemplates the provision of a silencer having a plurality of interconnected concentric chambers affording a continuous tortuous passage for the gas and sound waves, which chambers are separated by partition walls that are supported at one end only and are thus enabled to expand and contract freely without becoming loosened. In the preferred embodiment of this feature of the invention, a plurality of tubes are concentrically arranged between header members, and alternate tubes are secured at one end to opposite header members leaving the other ends of the tubes unsupported so that the tubes may expand and contract freely under different temperature conditions without becoming loosened or distorted.

Other objects of the invention are to provide a silencer of fabricated construction which is particularly designed for economical quantity production, to provide a light weight silencer having a simplified and thoroughly practical structure, to provide a silencer of the general type above indicated comprising a minimum number of component parts and to provide a silencer the parts of which may be easily and quickly assembled.

For the accomplishment of these objects and such others as may hereinafter appear, the invention consists in the features of construction and in the combinations and arrangements of parts hereinafter described and claimed, the particular advantages of which will be obvious to those skilled in the art.

The various features of the invention will be readily understood from the following description of the several forms thereof illustrated in the accompanying drawings, in which:—

Fig. 1 is a view in longitudinal section of a silencer constructed in accordance with what may be considered the preferred embodiment of the present invention;

Fig. 2 is a sectional view taken along the line 2—2 of Fig. 1;

Fig. 3 is a view similar to Fig. 1, showing a silencer having an alternative form of construction;

Fig. 4 is a view, partially in longitudinal section and partially in elevation, illustrating another alternative form of silencer construction;

Fig. 5 is a sectional detail view illustrating a feature of the invention relating to the construction of the tubular sheet metal members forming the concentric muffler chambers.

Referring to Figs. 1 and 2 of the drawings, the improved silencer therein illustrated is of fabricated construction and is composed entirely of sheet metal parts that are rigidly secured in assembled relation by means of tie-bolts. These sheet metal parts comprise an outer cup-like shell 15, a pair of annular channel members 16 and 17 which are adapted for assembly within the shell 15, and a flat disk or header plate 18 for closing one end of the silencer. The shell 15 is a one piece integral construction drawn into its finished shape from a circular sheet metal blank. As shown, the shell, has a cylindrical side wall and a flat end wall, the latter having an annular flange drawn lengthwise from a central opening therein to form a tubular conductor 19 coaxial with the cylindrical side wall of said shell and affording a port or passage 20 for the admission to the silencer of the gases and sound waves.

The channel members 16 and 17 are also, each of one piece construction, drawn from circular sheet metal blanks and these mem-

bers have cylindrical side walls and flat annular end walls, the side walls of one member being of greater diameter than the corresponding side walls of the other member. By virtue of this construction, the two channel members 16 and 17 are adapted for assembly with the mouths of the channels oppositely directed and with one side wall of each member interposed between 10 and spaced from the side walls of the other member. The end wall of the smaller channel member 17 is adapted for engagement with the end wall of the shell 15, while the end wall of the larger channel member 16 15 is adapted to be overlapped by the marginal portion of a disk or header plate 18.

In the present instance four tie-bolts 22 are employed to maintain the parts of the silencer in the assembled relation above 20 specified, although obviously, a greater or less number of tie-bolts may be used if desired. The tie-bolts 22 are disposed longitudinally of the silencer and extend through the annular space which is common to the 25 two assembled channel members, i. e. the space between the outer side wall of the smaller member 17 and the inner side wall of the larger member 16. At their ends, the tie-bolts 22 project through suitable holes 30 in the end walls of the channel members, in the end wall of the shell 15, and in the margin of the header plate 18. As shown, the portion of each tie-bolt between the opposed end walls of the two channel members 35 is square in cross-section and the opposite ends of the bolts are screw-threaded to receive clamping nuts 23. By thus using square bolts, suitable shoulders are provided for cooperating with the nuts 23 without 40 the necessity of reducing the diameter of the threaded ends of the bolts. By tightening the nuts 23 the end wall of the shell 15 will be rigidly secured to the end wall of the channel member 17 while the header 45 plate 18 will be rigidly secured to the end wall of the channel member 16. The length 50 of the square portions of the tie bolts is such that the peripheral edges of the channel members will be spaced from the opposed end faces of the other channel members or of the shell 15, as the case may be.

When assembled, the several component parts of the device will then be arranged in the positions clearly shown in Fig. 1. When 55 the parts are thus assembled a central muffler chamber 25 is provided between the inner side walls of the smaller channel member 17, and this chamber communicates at one end with the inlet port or passage 20. The 60 end walls of the shell 15, together with the end walls of the smaller channel member, constitute one end wall of the silencer while the opposite end wall of the silencer is formed by the header plate 18 and by the 65 end wall of the larger channel member. It

will be seen that the opposite end walls of the silencer are spaced from the adjacent peripheral edges of the channel members so that a series of concentric chambers are formed which are connected alternately at 70 opposite ends thereby providing a continuous tortuous passage through which the gases and sound waves are caused to flow from the central muffler chamber 25 to an annular discharge opening 26, the latter 75 being located between the side wall of the shell 15 and the adjacent outer side wall of the larger channel member.

In the above described silencer, inasmuch as the cylindrical walls separating the several concentric annular chambers are supported at one end only, these walls are enabled to expand and contract freely under different temperature conditions and consequently they have no tendency to become 80 distorted and loosened as they are repeatedly subjected to the heating action of the gases. The various parts are so firmly bound together by the tie-bolts that there is no tendency for them to work loose as a 85 result of the vibration and shocks to which they are subjected while the car is running. By designing the parts so that they may be drawn into shape from sheet metal blanks these parts can be produced very rapidly 90 and at a very low cost when manufactured in large quantities. The cost of manufacture of the silencers is further decreased by reason of the small number of parts to be assembled and the facility with which the 95 assembly and securing together of these parts may be effected. Furthermore, by the use throughout the silencer of thin sheet metal walls and partitions, a silencer of very 100 light weight has been provided.

The particular type of construction above described is especially adapted for silencers to be used on automobiles, farm engines, and small stationary engines where it is essential that the silencers shall be sold at a low 110 price. In manufacturing silencers of larger diameter, however, for use in connection with the more powerful engines, such for example as air-ship engines, it may be impracticable to produce silencer parts 115 of the requisite size by means of deep drawing operations. To enable certain features of the hereinbefore described construction and arrangement of parts to be utilized in connection with the construction of silencers 120 of large sizes, a modification of the present invention contemplates the production of the outer shell and the two channel members of the silencer each from several sheet metal blanks secured together by the process 125 of oxywelding.

The above mentioned construction is illustrated in Fig. 3. As therein shown, the cup-like shell within which the channel members are assembled, is made in three parts, 130

comprising two cylindrical tubes 30 and 31 and a centrally apertured disk 32. The outer and inner marginal portions of the disk 32 are bent laterally in opposite directions to 5 form annular flanges 33 and 34. One end of the tube 30 is welded to the flange 33 while one end of the tube 31 is welded to the flange 34, said tubes being arranged to extend in opposite directions from the disk 10 32 so as to form a member of substantially the same shape as the outer shell 15 in the form of silencer illustrated in Fig. 1.

Each of the channel members of this modification of the invention are constructed of 15 inner and outer tubes 35 and 36 and a sheet metal ring 37 the latter having its outer and inner margins bent laterally in the same direction to provide flanges 38 and the tubes 35 and 36 are welded at one end to said 20 flanges. Thus the tubes 35 and 36 constitute the outer and inner side walls, respectively, of the channel members while the rings 37 form the end walls of said channel members. The outer shell and the two channel members 25 constructed as just described, together with a disk 39, are assembled in the same manner as the corresponding parts of the preferred form of the invention and are similarly secured in place by tie-bolts of the 30 same construction as those already described.

This alternative construction may be employed wherever it is desired to eliminate the difficulties of drawing, and while it is more expensive in quantity production to 35 produce the silencer parts by oxywelding smaller parts together than by forming the whole from a single blank by drawing operations, the parts may be economically produced in small quantities by the employment of the above described oxywelding process. It will be seen that the silencer illustrated in Fig. 3 is constructed entirely of sheet metal and the partition walls between the concentric muffler chambers are 40 supported at one end only as in the preferred form of the invention so that they are free to expand and contract without danger of becoming loosened. Furthermore, the type of construction shown in Fig. 3 45 possesses the same advantageous features of lightness and ease of assembly already referred to in connection with the previously described type.

Fig. 4 illustrates a muffler of a somewhat 50 further modified construction which is made entirely of sheet metal without the deep cup drawing and repeated annealing operations required for the construction in Fig. 1 and without the welding required for the construction in Fig. 3. In this form of silencer the outer shell thereof is shaped substantially as in the forms already described 55 but is composed of two parts 43 and 44 which are adapted to be maintained in assembled relation to each other by means of

tie-bolts 45 of the same sort as those used in the other forms of silencers. As shown, the part 43 consists of a cylindrical tube having one end thereof turned inwardly at right angles to the side of the tube to form 70 a flange 46 while a similar flange 47 is turned outwardly from one end of the tube 44 and is adapted to overlap the flange 46 as shown.

In this form of silencer four separate 75 cylindrical tubes 48, 49, 50 and 51 are substituted for the two annular channel members of the form previously described, the tubes 48 and 50 being provided at one end with flanges 52 which are overlapped and 80 apertured to receive the tie-bolts 45 and these flanges and also the flanges 46 and 47 are clamped together between the shoulders and nuts at one end of the tie-bolts so that the parts associated with said flanges are 85 rigidly secured in place. The tubes 49 and 51 are similarly flanged as shown at 53, the flanges 53 overlapping and being apertured to receive the opposite ends of the tie-bolts. The flanges 53 together with the marginal 90 portion of an end plate 54, through which the tie-bolts also extend, are clamped between the adjacent shoulder and nuts of the tie-bolts. It will be seen that the general 95 relation of the passages in this form of silencer are the same as in the preceding forms and the gases and sound waves will travel through the same course and be similarly acted upon therein.

To assist in breaking up the sound waves 100 as the latter pass through any of the above described silencers the opposite side walls of each annular muffler passage may be provided with annular portions 64 which are inclined inwardly with respect to the direction of travel of the waves through said 105 chambers to provide what may be termed "reverse megaphone" sections 65. These sections 65 will be engaged by a certain number of the sound waves advancing through 110 the muffler chambers and will operate to prevent further advance thereof. The angle of inclination of the wall portions 64 is not sufficient however to appreciably retard the 115 flow of the gases through the muffler chambers. This feature is illustrated in Fig. 5.

The invention has been herein disclosed for illustration purposes in its preferred embodiment and in several alternative forms, but it is to be understood that 120 the invention is capable of being still further changed and modified to adapt it for various conditions of use and that the scope of the invention is defined by the appended claims rather than by the foregoing description.

What I claim is:

1. In a silencer of the type having a series of interconnected concentric chambers affording a continuous tortuous passage for 130

the gases and sound waves, a plurality of spaced elongated cylindrical partition walls separating said chambers, oppositely facing header members for completely closing the 5 opposite ends of said chambers, said partition walls being supported alternately from opposite header members, and tie bolts connected to said header members and means on said bolts between said header members for 10 spacing the same apart a distance greater than the length of said partition walls, whereby the ends of said partition walls and the adjacent header members will be separated by passages affording the means of 15 communication between adjacent concentric chambers.

2. In a silencer of the type having a series of interconnected concentric chambers affording a continuous tortuous passage for 20 the gases and sound waves, a plurality of spaced elongated cylindrical partition walls separating said chambers, header members separable from said partition walls for closing the opposite ends of said chambers, and 25 tie-bolts serving both for supporting the header members in spaced relation and for rigidly securing the partition walls to the header members.

3. In a silencer of the type having a series 30 of interconnected concentric chambers affording a continuous tortuous passage for the gases and sound waves, a plurality of separable annular channel members each having an annular base and side walls perpendicular to said base, said members being adapted for assembly in reversed positions with their annular bases spaced apart and in coaxial relation, with one side wall of each channel member interposed between 35 and spaced from the side walls of the other channel member and from the annular base of said member, spaced apart header plates for supporting said channel members, and 40 tie bolts serving both for securing the annular bases of said channel members to the header plates and to rigidly maintain the channel members in the relation to each other above specified.

4. A silencer comprising a plurality of 50 separable annular channel members adapted for assembly in reversed positions with their annular bases spaced apart and in coaxial relation, with one side wall of one member interposed between and spaced from the side 55 walls of an adjacent member, and a plurality of bolts extending axially through the channels and bases of one or more of said channel members for rigidly supporting said members in the relative positions specified 60 and with the peripheral edges of each channel member spaced from the base of the other member, thereby providing a series of interconnected concentric chambers affording a continuous tortuous passage for 65 the gases and sound waves.

5. A silencer comprising a cup member having a base centrally apertured for the passage of the sound propagating medium, two separable annular channel members of different diameters adapted for assembly in 70 reversed positions with their annular bases spaced apart and coaxial with said cup member with one side wall of each channel member interposed between and spaced from the side walls of the other channel member and the outer side wall of the larger channel member spaced from the side wall of said cup member, a disk for closing the central passage through the larger channel member at one end of the silencer, and means serving both for securing the annular base of the smaller channel member to the base of said cup member and the marginal portion of said disk to the annular base of the larger channel member and for maintaining the channel members with their side walls in the relation specified and with the peripheral edges of each channel member spaced from the annular base of the other channel member. 80

6. A silencer comprising a cup member having a base centrally apertured for the passage of the sound propagating medium, a separable annular channel member coaxially disposed within said cup member with its annular base secured to the base of said cup member, a second separable annular channel member having its inner side wall interposed between and spaced from the side walls of the first channel member and its outer side wall interposed between and spaced from the outer side wall of said channel member and the side wall of said cup member, a disk having its marginal portion secured to the annular base of the second channel member, and means for rigidly maintaining the channel members in the relative positions specified and with the peripheral edges of each of said channel members spaced from the annular base of the other member and for securing the first channel member to said cup member and the second member to said disk. 100

7. A silencer comprising a cup member having a base centrally apertured and an annular flange outwardly turned in an axial direction from said aperture in its base to provide an inlet conductor for conveying to the silencer the gases and sound waves, a separable annular channel member coaxially disposed within said cup member with its annular base secured to the base of said cup member, a second separable annular channel member having its inner side wall interposed between and spaced from the side walls of the first channel member and its outer side wall interposed between and spaced from the outer side wall of said channel member and the side wall of said cup member, means for closing the 110 120 125 130

central passage through the second channel member at the end remote from the base of said cup member and means for maintaining the channel members in the relative positions specified and with the peripheral edges of each of said channel members spaced from the annular base of the other channel member.

8. A silencer comprising a plurality of separable annular channel members adapted for assembly in reversed positions with their annular bases spaced apart and in coaxial relation with one side wall of one member interposed between and spaced from the side walls of an adjacent member, and a plurality of tie-bolts extending axially through the channels of one or more of said channel members, said bolts being shouldered to engage the inner faces of the opposed annular bases of said members and having screw-threaded ends beyond said shoulders projecting through the bases of said members, and nuts on said threaded bolt ends for clamping said members against said shoulders to support said members in the relation specified, the shoulders of said tie-bolts being located so that the peripheral edges of each channel member will be spaced from the base of the other channel member.

9. A silencer comprising a plurality of separable annular channel members adapted for assembly in reversed positions with their annular bases spaced apart and in coaxial relation with one side wall of one member interposed between and spaced from the side walls of an adjacent member, and a plurality of the bolts extending axially through the channels of one or more of said channel members, the opposite ends of the bolts being screw-threaded and adapted to project through holes in the annular bases of said members and the portion of the bolt between said threaded ends being square in cross-section and of the same diameter as said threaded ends thereby providing shoulders adjacent said ends to engage the inner faces of the opposed annular bases of said members and to space the peripheral edges of each channel member from the base of the other channel member, and nuts on said threaded bolt ends for clamping said members against said shoulders to support said members in the relation specified.

10. In a silencer of the type having a series of interconnected concentric chambers affording a continuous tortuous passage for the gases and sound waves, the provision in said chambers intermediate the ends thereof of a longitudinal section of restricted transverse area interposed between sections of maximum area, said restricted area section having gradually tapering side walls for breaking up the sound waves without appreciably retarding the passage of the medium of travel of said waves.

11. A silencer comprising a cup member constructed of separate pieces joined together, said member having a base centrally apertured for the passage of the sound propagating medium, two separable annular channel members of fabricated construction and different diameters adapted for assembly in reversed positions with their annular bases spaced apart and coaxial with said cup member with one side wall of each channel member interposed between and spaced from the side walls of the other channel member and the outer side wall of the larger channel member spaced from the side wall of said cup member, a disk for closing the central passage through the larger channel member at one end of the silencer, and means serving both for securing the annular base of the smaller channel member to the base of said cup member and the marginal portion of said disk to the base of the larger channel member and for maintaining the channel members with their side walls in the relation specified and with the peripheral edges of each channel member spaced from the base of the other channel member.

12. A silencer comprising a cup member having an annular flange outwardly turned in an axial direction from an aperture in its base to provide an inlet conductor for conveying to the silencer the gases and sound waves, said cup member constructed of two annular parts having overlapping portions constituting said base, a separable annular channel member adapted for assembly within and coaxial with said casing, said member comprising outer and inner concentric side walls having respectively inturned and outturned annular flanges at one end thereof arranged in overlapping relation to constitute the annular base of said member, a second separable annular channel member of greater diameter than the first channel member and similarly constructed, said second channel member adapted for assembly in the silencer with its inner side wall interposed between and spaced from the side walls of the first channel member and its outer side wall interposed between and spaced from the outer side wall of said channel member and the side wall of said cup member, a disk having its marginal portion adapted to overlap the annular base of the second channel member, and tie bolts extending through said disk and through said overlapped portions of said cup member and of said channel members to rigidly secure said parts together in the relative positions specified and with the peripheral edges of the channel members spaced from the end walls of the other channel member.

In testimony whereof I have affixed my signature.

HIRAM PERCY MAXIM.
